UNITED STATES PATENT OFFICE.

CHARLES LAUFFET, OF PARIS, FRANCE.

APPARATUS FOR HAMMERING PISTON-RINGS.

1,377,967.

Specification of Letters Patent. Patented May 10, 1921.

Application filed September 2, 1919. Serial No. 321,231.

To all whom it may concern:

Be it known that CHARLES LAUFFET, of 46 Rue St. Ferdinand, Paris, France, a citizen of the French Republic, (whose post-office address is 46 Rue St. Ferdinand, Paris, France,) has invented certain new and useful Improvements in Apparatus for Hammering Piston-Rings, of which the following is a specification.

10 Rings for explosion motor pistons, the internal surface of which has a series of grooves or recesses produced by hammering with the object of increasing the elasticity of these rings and thus enabling them to 15 act more effectively are well known.

The present invention consists in an apparatus which enables the hammering of the said rings to be effected automatically the variations of spacing being made with 20 very great precision and moreover being capable of modification as desired by a very simple operation.

This machine comprises two essential parts; on the one hand the mechanism for 25 operating the graver which during the working is subjected to a uniform alternating rectilineal movement; on the other hand a mechanism serving to cause the ring that is to be worked to rotate in front of the 30 graver the rotary movement thus imparted to the ring being uniformly varied so as to obtain the desired variations in the spacing.

In the accompanying drawing one form 35 of hammering apparatus in accordance with the invention is illustrated by way of example.

Figure 1 is a front elevation of the whole apparatus.

Fig. 2 is a plan view thereof.

40 Fig. 3 is a detail view on a larger scale showing in front elevation the device by means of which the graver is operated.

Fig. 4 is a section of the same mechanism taken through I I in Fig. 3.

45 Figs. 5 to 10 are diagrams explanatory of the mechanism by means of which the varied uniform rotary movement of the ring that is to be hammered is produced.

In this apparatus as has been stated the 50 ring 1 which is to be hammered rotates opposite the graver 2. The alternating rectilineal movement of the said graver is produced in the following manner: The roller 3 which is firmly connected with the graver 2 is raised by the teeth of the ratchet wheel 4. When the roller leaves a tooth of the said

wheel the springs 5 cause it to drop abruptly; the graver thus strikes the point in the ring which is in front of it at that moment. The graver is guided in its movement by the slide 7' which moves between the exterior slides 7 that are mounted on the fixed frame 8. A pin 9 enables the graver 2 to be made stationary when this is expedient.

The ratchet wheel 4 is actuated by the main shaft 10. On this shaft (see Fig. 2) the staged pulleys 11 are mounted which enable the speed of the apparatus to be varied.

The ring 1 which is to be hammered is supported by a crown 12 which is put in place at each operation by means of sockets 13 in which the screws 14 engage which are fixed in the casing 15.

The casing 15 rotates around the frame 8. In order to insure the actuating of the ring a toothed rim 16 is placed on it which is actuated by a chain 17.

The chain is operated by a toothed wheel 18 in which an opening 19 is cut that runs from the center and has a radial direction. In the opening 19 the shaft 20 of the pulley 21 engages. Through the medium of the belt 22 this pulley receives the movement of 85 the pulley 23 that is mounted on the main or actuating shaft 10 (see Figs. 1 and 2).

This arrangement enables the wheel 18 to be ex-centered more or less in relation to the pulley 21 for the purpose of effecting the 90 variations of speed.

The chain 17 is put under tension by a loose pinion 24 fixed to the end of a lever 25 that moves around a pin 26 a spring 27 having a constant tendency to lower the 95 said lever and consequently the pinion 24. A return pinion 28 is suitably arranged so that the arc embraced by the chain 17 on the wheel 16 may always be sufficient.

The action of this mechanism is as follows: The mechanism by means of which the graver is operated having been immobilized through the medium of the pin 9 and the ring which has to be hammered having been mounted in the crown 12 the 105 whole is put in place so that the point of junction is opposite the graver for example. The eccentricity of the wheel 18 in relation to the pulley 21 having been suitably regulated in accordance with the variations of 110 speed which it is desired to obtain the pin 9 is removed and the hammering effected.

The mechanism by means of which the ring is rotated acts in the following manner: If the centers o and o' of the actuating pulley 21 and the wheel 18 (x) coincide 5 the ring is subjected to a rotary motion of uniform speed. In this case the recesses or grooves formed in the ring are thus uniformly spaced (case of Fig. 9).

If it be desired to obtain recesses with 10 variable spacing for the production of rings of the kind described in the before mentioned patent application the wheel 18 is ex-central more or less in relation to the pulley 21 by moving the pin 20 in the opening 19. 15 Fig. 1 shows the position of maximum eccentricity. This mechanism acts as shown by the diagrams of Figs. 5, 6, 7, 8 and 10. When the apparatus works in these conditions the center o' of the wheel 18 rotates 20 around the center 9 of the actuating pulley 21. It is easy to understand if the diagrams of Figs. 6, 7, 8 and 10 be considered that in these conditions the rotary speed of the wheel X (18) increases from a to f . 25 that is to say during half the course, then diminishing from f to a , the speeds being the same for the symmetrical points b and b' , c and c' , d and d' , e and e' . The difference between the minimum of speed (at a) 30 and the maximum (at f) can be modified as desired by varying the distances between the centers o and o' . The variations in the rotary speed of the wheel 18 result from the fact that the various points of the circumference X are at variable distances from the center o in consequence of the eccentricity. 35 On the other hand the wheel 16 being connected with the wheel 18 through the chain,

the rotary speed of the wheel 16 at each instant is equal or proportional to that of 40 the wheel 18 according to the respective diameters of these two wheels. The ring itself which is firmly connected with the wheel 16 thus rotates with a uniformly varied movement the speed being at a minimum at the point in the said segment diametrically opposite to the point of junction. It is evident that the greater the speed of the ring the greater is the distance 45 between the recesses produced by the graver. 50

I claim:—

1. A machine for hammering piston rings comprising a hammer, means including a ratchet wheel and roller for reciprocating said hammer, means for supporting a piston ring and driving means for imparting a uniform reciprocating motion to the hammer and adapted to be adjusted to impart either a uniform rotary or a uniformly varied 55 rotary motion to the ring. 60

2. A machine for hammering piston rings comprising a hammer, means including a ratchet wheel and roller for reciprocating said hammer, means for supporting a piston ring and means including a wheel and 65 actuating pulley for rotating the piston ring and adjusting means whereby the center of the wheel is movable in relation to the center of the pulley to vary the motion conveyed to the ring. 70

In testimony he has affixed his signature, in presence of two witnesses.

CHARLES LAUFFET.
